UNITED STATES PATENT OFFICE.

HAROLD G. RICE, OF PORTLAND, OREGON.

BOTTLE-CAPPER.

1,257,637.

Specification of Letters Patent. Patented Feb. 26, 1918.

Application filed October 29, 1917. Serial No. 199,105.

To all whom it may concern:

Be it known that I, HAROLD G. RICE, a citizen of the United States, residing at Portland, in the county of Multnomah and State 5 of Oregon, have invented a new and useful Bottle-Capper, of which the following is a specification.

It is the object of this invention to provide a simple means adapted to be carried 10 and manipulated in the hand of an operator, whereby a cap may be seated on the neck of a bottle, novel means being provided for guiding the cap into a thimble which constitutes a part of the device, and for receiving 15 the cap after the same has been seated in the capper.

It is within the province of the disclosure to improve generally and to enhance the utility of devices of that type to which the 20 present invention appertains.

With the above and other objects in view, which will appear as the description proceeds the invention resides in the combination and arrangement of parts and in the 25 details of construction hereinafter described and claimed, it being understood that changes in the precise embodiment of the invention herein disclosed can be made without in the scope of what is claimed without de- 30 parting from the spirit of the invention.

In the accompanying drawings:—

Figure 1 shows in side elevation, a bottle capper constructed in accordance with the present invention;

Fig. 2 is an end elevation of the capper, distant parts being omitted; and

Fig. 3 is a fragmental side elevation, showing the capper in operative relation to the bottle, parts being broken away, and parts 40 appearing in section.

In carrying out the present invention there is provided a bar-like handle 1 which is sufficiently short to be manipulated in the hand of an operator. The handle 1 prefer- 45 ably although not necessarily is made of wood and is rounded at one end, as shown at 2, to coöperate with the palm of the hand of the operator. Intermediate its ends, the handle 1 is reduced in diameter and tapered 50 at 3, so that it may be gripped readily. The handle 1 is reduced in diameter to form a stem 4 and to form a circumscribing shoul- der 5. A thimble 6, which preferably is made

of metal, surrounds the stem 4 and abuts at its inner end against the shoulder 5. The 55 outer end of the thimble 6 is extended beyond the outer end of the stem 4. The thimble is circumferentially grooved, as shown at 7, to form an internal rib 8, engaging the stem 4, to hold the thimble on the stem. The 60 thimble 6, further, is laterally flared, as shown at 9, in alinement with the outer end face of the stem 4, to receive a bottle cap 12, when the cap abuts against the end of the stem 4. The thimble 6 at its extreme 65 end is outwardly flared to form a bell-shaped mouth 10 adapted to receive the cap 12 and to guide the cap into the thimble, into abut- ment with the end of the stem 4.

In practical operation, the cap 12 is in- 70 troduced into the thimble 6, as above de- scribed, and abuts against the end of the stem 4. The cap 12 is then pressed down onto the bead 14 at the upper end of a bot- tle 15.

From the foregoing it will be observed that a simple but useful means is provided whereby, without the use of expensive ma- chinery of any kind, a cap of the well known kind may be seated on the end of the neck 80 of a bottle.

Having thus described the invention, what is claimed is:—

A bottle capper comprising a bar-like han- 85 dle sufficiently short to be manipulated in the hand of an operator, the handle being re- duced in diameter to form a stem and to form a circumscribing shoulder; and a thimble surrounding the stem and abutting at its inner end against the shoulder, 90 the outer end of the thimble being ex- tended beyond the outer end of the stem, the thimble being circumferentially grooved to form an internal rib engaging the stem, the thimble being laterally flared in aline- 95 ment with the outer end of the stem to receive a bottle-cap, and being outwardly flared at its extreme end to form a cap- receiving mouth.

In testimony that I claim the foregoing as 100 my own, I have hereto affixed my signature in the presence of two witnesses.

HAROLD G. RICE.
